UNITED STATES PATENT OFFICE.

OTTO W. LINSTRUM, OF PERDUE, ILLINOIS.

THILL-COUPING.

SPECIFICATION forming part of Letters Patent No. 626,622, dated June 6, 1899.

Application filed April 26, 1899. Serial No. 714,512. (No model.)

To all whom it may concern:

Be it known that I, OTTO W. LINSTRUM, a citizen of the United States, residing at Perdue, in the county of Ford and State of Illinois, have invented a new and useful Thill-Coupling, of which the following is a specification.

This invention relates to thill-couplings, and has for its object to provide such a device which may be readily positioned and removed and in which the ends of the axle-clip are relieved of strain by disposing the line of draft above the same and against the rear side of the axle.

15 A further object is to utilize the draft to positively lock the device against accidental loosening.

With these objects in view the present invention consists in the combination and arrangement of parts, as will be hereinafter more fully described, shown in the accompanying drawings, and particularly pointed out in the appended claims.

25 In the drawings, Figure 1 is a perspective view of the coupling. Fig. 2 is a longitudinal sectional view thereof. Fig. 3 is a detail perspective view of the thill-iron and link. Fig. 4 is a detail perspective view of the tie-bar for the axle-clip. Fig. 5 is a detail perspective 30 view of the clamp for locking the device in its operative position.

Corresponding parts are designated by like reference characters in all the figures of the drawings.

35 Referring to the accompanying drawings, 1 designates an axle having the usual clip 2 fitted thereto in the ordinary manner. The tie-bar for the ends of the clip is designated by 3, being flat, as usual, but extending a suitable 40 distance both in front and rear of the axle. Near its front end, adjacent to the clip and upon its upper face, the tie-bar is provided with an upstanding shoulder 4, having its front upright face 5 concaved vertically and rounded evenly into the upper face of the tie-bar, whereby an open-front socket or 45 recess is provided for the seating or reception of the thill-iron. It is preferable to line this socket with a strip of leather 6, secured to the front end of the tie-bar by a suitable fastening 7. At its rear end the tie-bar is provided with a reduced tongue 8, upon which is adapted to be mounted the clamp for fastening the device in its operative position.

By reference particularly to Fig. 5 it will be seen that the clamp comprises a substantially rectangular body 9, provided at one end with a hook 10, having the opening or mouth thereof disposed upwardly, and at the opposite end of the body with an upwardly-extending operating thumb-lever 11, which is slightly inclined toward the opposite or hook end of the body. The latter is further provided with a socket or recess 12, opening downward through the bottom of the body 65 and outward through the lever end thereof. In mounting the clamp upon the tie-bar the tongue 8 of the latter is loosely received into the socket or recess 12 of the body of the clamp and a pivot-pin 13 is passed transversely 70 through the latter and the tongue intermediate of the hook 10 and lever 11, whereby the clamp is pivotally mounted upon the tie-bar in rear of the axle.

As best illustrated in Fig. 3, the thill-iron 14 is of common form, having the usual pivot-bolt 15 extending transversely through the thill-eye 16 and projecting at opposite sides thereof. Pivotally connected to the thill-iron is a substantially U-shaped link 17, having 80 its opposite ends flattened, as at 18, and provided with transversely-alined openings to receive the ends of the pivot-bolt 15.

In the operation of the device, the tie-bar and clamp being mounted as hereinbefore 85 described, the thill-eye 16 is seated in the socket formed by the upstanding shoulder 4 and the end of the tie-bar being received between the opposite sides of the link and projecting beneath the eye of the thill-iron. It 90 will be noted by reference to Fig. 2 that the thill-irons are adapted to rest upon the front portions of the respective tie-bars, and thereby support the ends of the thills away from the ground or floor, and thereby prevent accidental breaking of the thills. As indicated in dotted lines in Fig. 2 of the drawings, the link extends obliquely downward and rearward beneath the axle and embracing the tie-bar. The clamp having been previously 100 thrown into a vertical position, (shown in dotted lines,) the closed end of the link is engaged with the hook 10 of the clamp, and by operation of the thumb-lever 11 the clamp may be thrown around into its locked position, as indicated in the full lines. The lever is adapted to engage against the rear side of the axle-clip, and by reason of the rearward

inclination of the lever the line of draft upon the link is disposed above the pivot of the clamp, whereby the draft is adapted to bind the thumb-lever tightly against the rear side 5 of the axle and prevent accidental loosening or disengagement of the device. As the thumb-lever engages the axle-clip it will be noted that the clip receives the wear of the thumb-lever, and thereby protects the wooden 10 axle.

In order that the device may be applicable to axles of different sizes, the opening 19, formed through the tie-bar in front of the axle for the reception of one of the ends of 15 the axle-clip, is elongated longitudinally.

The present invention provides an exceedingly effective and durable coupling, as the draft is distributed between the ends of the axle-clip and the rear side of the axle, thus 20 relieving the ends of the clip of the greater part of the strain, and thereby prolonging the life of the device. Furthermore, as the link engages against the under side of the axle and the line of draft is disposed above the pivot 25 of the clamp the latter is conveniently and effectively locked in the operative position of the device. The clamp holds the eye of the thill-iron firmly against the lining of the socket formed by the upstanding shoulder 4, 30 and thereby prevents rattling of the thill-iron in the socket. As the latter socket is open at the front thereof, the positioning and removal of the thills is greatly facilitated thereby.

Changes in the form, proportion, size, and 35 the minor details of construction within the scope of the appended claims may be resorted to without departing from the spirit or sacrificing any of the advantages of the present invention.

40 Having thus described the invention, what is claimed is—

1. In a thill-coupling, the combination with an axle-clip, of a tie-bar therefor, having a socket at its front end and a clamp at its rear 45 end, and a thill-iron carrying a link, the eye of the thill-iron being adapted to be seated in the socket, the link to engage the clamp, and the latter to be thrown into engagement with the axle, whereby the clamp is locked in 50 the operative position of the device, substantially as shown and described.

2. In a thill-coupling, the combination with an axle-clip, of a tie-bar therefor having a socket provided at its forward end, a clamp pivoted to the opposite end of the tie-bar in 55 rear of the axle and provided with a hook at its rear end and an upwardly-extending thumb-lever at its opposite end, and a thill-iron, having a link pivoted thereto, the eye 60 of the thill-iron being adapted to be seated in the socket, the link to engage the hook of the clamp, and the thumb-lever to be thrown into engagement with the axle, whereby the line of draft is disposed above the pivot of the 65 clamp, substantially as and for the purpose set forth.

3. In a thill-coupling, the combination with an axle-clip, and a tie-bar having a socket at the forward end thereof, of a clamp provided at the rear end of the tie-bar, a thill-iron, and a substantially U-shaped link pivoted at its 70 opposite ends to the thill-iron, the latter being adapted to be seated in the socket of the tie-bar, and the link to engage the clamp embracing the tie-bar and extending beneath 75 and against the lower side of the axle, substantially as shown and described.

4. In a thill-coupling, the combination with an axle-clip, of a tie-bar therefor adapted to extend both in front and in rear of the axle 80 and having a socket provided at its forward end, a clamp having a hook at its rear end, an upwardly-extending thumb-lever at its forward end, a recess provided in the under side opening out through the forward end 85 thereof and adapted to loosely receive the rear end of the tie-bar, the clamp being pivoted thereto and adapted to swing vertically thereon, and a thill-iron having a link pivoted thereto and adapted to engage the hook of 90 the clamp, substantially as shown and described.

5. In a thill-coupling, the combination with an axle-clip, of a tie-bar adapted to extend both in front and in rear of the axle and provided near its front end with an upstanding shoulder concaved upon its front side and forming with the tie-bar an open socket, a clamp provided upon the rear end of the tie-bar, and a thill-iron having a link pivoted 100 thereto and adapted to extend beneath the axle and engage the clamp, substantially as shown and described.

6. In a thill-coupling, the combination of an axle-clip, a tie-bar adapted to extend both 105 in front and in rear of the axle and having an upstanding shoulder near its front end, a clamp pivoted to the rear end of the tie-bar and comprising a substantially rectangular body having a hook at the rear end, and an 110 upstanding rearwardly-inclined thumb-lever at the forward end thereof, and provided with a recess opening out through the bottom and the lever end of the body, the recess being adapted to loosely receive the rear end of 115 the tie-bar, a pivot-pin passing transversely through the body of the clamp and the tie-bar whereby the clamp is adapted to be swung vertically, and a thill-iron having a pivot-bolt extending loosely through the eye thereof, and a substantially U-shaped link, having 120 its ends provided with transversely-alined eyes pivotally receiving the respective ends of the pivot-bolt, substantially as shown and described.

In testimony that I claim the foregoing as my own I have hereto affixed my signature in the presence of two witnesses.

OTTO W. LINSTRUM.
